UNITED STATES PATENT OFFICE.

JUNE B. MOREY, OF BROOKLYN, NEW YORK.

WASHING-MACHINE LATCH.

Application filed April 25, 1925. Serial No. 25,732.

This invention relates to washing machine latches and more particularly to latches for holding open the door or doors of the revolving member or drum of a large power driven machine. In machines of this type it is frequently necessary for a man to get inside for repairing or cleaning the same or other purposes. At such times it is essential that the door of the revolving member or drum remain open and be positively prevented from closing. It is also necessary to provide a catch which will continue to retain said door open even though the drum revolves slightly.

The objects of the invention are to provide a catch for the door of a washing machine which positively engages said door and which must be manually disengaged before said door will close; to continue to engage said door by a catch during slight rotation of the drum; to provide a catch which is out of the way; is adapted to use with single or double doors; may be easily adjusted and made with duplicate parts; to secure simplicity of construction and operation; and to obtain other advantages and results as may be brought out in the following description.

Referring to the accompanying drawing in which like numerals of reference indicate similar parts throughout the several views:

Figure 1 is a cross-sectional view of a washing machine with the door to the rotating drum held open by my improved catch;

Figure 2 is a plan view of my improved catch mounted on a portion of a washing machine with double doors, parts being in section for greater clarity;

Figure 3 is a side elevation of the said catch, and

Figure 4 is a plan view corresponding to Figure 2, showing the invention applied to a washing machine with a single door.

In the specific embodiment of the invention illustrated in said drawing, the reference numeral 1 indicates the housing or outer drum of a washing machine, said housing being shown as cylindrical. Within the housing 1 is a concentric rotating member or drum 2. Both the housing and drum have door openings 3 and 4 respectively with suitable closures therefor. In

the drawing is shown a hinged door 5 for 55 rotating member or drum 2 adapted to open outwardly and upwardly through the opening 3 in the housing 1. It is this door 5 that my present invention is intended to retain open when desired. It may here be 60 noted that some machines are provided with two doors arranged longitudinally of the drum with a space between the ends thereof as shown in Figure 2.

My improved catch comprises a bracket 65 6 secured by screws or otherwise adjacent the upper edge of opening 3 in said housing at a position between the planes of the adjacent ends of the drum doors 5. Said bracket 6 provides a recess 7 opening toward the opening of said housing and adapted to receive the ends of adjustable catch members. In the construction shown more particularly in Figures 1, 2 and 3, are shown catch members 8, 8 which are preferably duplicates, having their outer ends 9, 9, offset in opposite directions, and the inner ends 10, 10 flatwise together so the two members assembled resemble a tuning fork in appearance. Said outer ends 9, 9 80 are preferably offset so the distance from the outer face of one to the outer face of the other is substantially equal to the distance between the ends of the doors. At the outer ends of said members and on the 85 outer sides thereof are wedge shaped latches 11, 11, the small ends of which are next to the outer ends of said members. The parts are so arranged and shaped that as the doors 5 are opened the edges thereof 90 will engage the sloping portions of said wedges and swing the catch members until the ends of said latches snap in behind the marginal edges of said doors. It is to be observed that the catch members are preferably resilient so as to obtain this snapping engagement of the latches.

If preferred, a spiral spring 12 pressing outwardly between the catch members may be employed as the entire or as supplemental resilient means for securing this snapping engagement. A bolt 13, positioned crosswise between said catch members free to slide with respect to said members not only supports said spiral spring, but constitutes a 100 stop for limiting the outward swing of said members to the distance between its ends of the doors.

From the above description it is to be understood that the inner ends of said catch members are side by side and are slid into and held fixed within recess 7 of bracket 6, said bracket being provided with a set screw 14 at one side for that purpose. The recess 7 in said bracket 6 is of such shape as to substantially fit the width of said members, but large enough vertically and longitudinally to enable said members to be inserted more or less or tilted slightly up or down so as to enable the catch members to be properly adjusted with respect to the doors.

In operation it will be seen that the doors, either or both, may be swung up and engaged by the latches forming part of said catch members. Since these latches operate to engage the doors at their side edges, they may slide along said edges without releasing the doors, and therefore, even though the drum may rotate somewhat, the door will merely slide back and forth and continue to be held open.

Where the machine is equipped with only one door, it is unnecessary and in no way desirable to employ a double catch. It is accordingly believed within the scope of the invention to employ a fixed catch member in place of one of the resilient catch members above described for the spiral spring to engage against and to support the bolt limiting swing of said resilient member. As illustrative of such construction, I have shown in Figure 4 a portion of a washing machine housing 1, drum 2, with door 5 as heretofore described as well as a bracket 6 with recess 7 and a pair of catch members mounted therein, one of which, 8, next to the door 5 has an offset outer end 9 and an inner end 10, the outer end having a wedge-shaped latch 11 all as heretofore described. The other catch member, as shown in Figure 4, comprises a straight and preferably non-resilient bar 15. Said bar 15 and the inner end 10 of the other catch member are positioned flatwise together and mounted in the recess of the bracket, being held in adjusted position by a set screw 14. A bolt 13 extends between the two members 8 and 15, limiting resilient swinging of the one member 8 outwardly. A spring 12 on said bolt between said members will tend to maintain the resilient member in its outward position.

Obviously other detail changes and modifications may be made in the manufacture and use of my improved washing machine catch, and I do not wish to be understood as limiting myself to the exact structure shown except as set forth in the following claims when construed in the light of the prior art.

Having thus described the invention, I claim:—

1. In combination with a washing machine having a hinged door, a catch fixedly mounted on said washing machine, said catch engaging said door in open position at the side edge of said door. 65

2. In combination with a washing machine having a hinged door, a resilient catch fixedly mounted on said washing machine, said catch adapted to snap under and engage said door at the side edge thereof, said catch being positioned to engage 75 and hold the door when said door is open.

3. In combination with a drum washing machine having a pair of hinged doors, a catch fixedly mounted on said washing machine, said catch arranged between the paths 80 of swinging of said doors and having means for separately engaging and holding said doors.

4. In combination with a washing machine having a housing with an opening and a drum within the housing having an opening, the opening in said drum having a pair of hinged doors longitudinally separated, a catch on the housing arranged between the paths of swinging of said doors and having means for separately engaging said doors at their side edges and holding 85 said doors open. 90

5. In combination with a washing machine having a hinged door, and means for retaining said door in abnormal open position comprising a bracket on the washing machine, a resilient catch member projecting from said bracket, and means on said catch member for engaging said door at its side edge and hold said door open. 95 100

6. In combination with a washing machine having a hinged door, and means fixedly mounted on said washing machine for retaining said door in abnormal open position comprising a bracket, a catch member projecting from said bracket adapted to engage said door at its side edge, and resilient means for pressing said catch member toward the side edge of said door. 105 110

7. In combination with a washing machine having a hinged door, and means fixedly mounted on said washing machine for retaining said door in abnormal open position comprising a bracket, a catch member projecting from said bracket adapted to engage said door at its side edge, resilient means for pressing said catch member toward the side edge of said door, and means for limiting the swinging of said catch member by said resilient means. 115 120

In testimony whereof I affix my signature.

JUNE B. MOREY.
